United States Patent Office

Des. 203,126
Patented Dec. 7, 1965

203,126

CLOCK

Max E. Schlenker, Peru, Ill., assignor to General Time Corporation, New York, N.Y., a corporation of Delaware

Filed Apr. 27, 1965, Ser. No. 84,980

Term of patent 14 years

(Cl. D42—7)

FIG. 2

FIG. 1

FIG. 3

FIG. 4

FIG.5

FIG.6

FIG. 1 is a top plan view of a clock showing my new design, in closed condition;

FIG. 2 is a rear elevational view thereof;

FIG. 3 is a side elevational view thereof;

FIG. 4 is a front elevational view thereof;

FIG. 5 is a front elevational view thereof showing the clock in partially opened condition; and

FIG. 6 is a side elevational view of the clock in fully opened condition.

I claim:

The ornamental design of a clock, substantially as shown.
